C. L. LILLEBERG

ELECTRIC CABLE

Filed Dec. 7, 1921

Inventor:

Charles L. Lilleberg

By L. L. Gragg Atty.

UNITED STATES PATENT OFFICE.

CHARLES L. LILLEBERG, OF CHICAGO, ILLINOIS.

ELECTRIC CABLE.

Application filed December 7, 1921. Serial No. 520,512.

To all whom it may concern:

Be it known that I, CHARLES L. LILLEBERG, citizen of the United States, residing at Chicago, in the county of Cook and State 5 of Illinois, have invented a certain new and useful Improvement in Electric Cables, of which the following is a full, clear, concise, and exact description.

My invention relates to electric cables and 10 has for its object the provision of an improved construction, whereby the wires of the cable are accessible along the length of the cable for circuit connection.

The cable of my invention is provided 15 with an enclosing conduit formed with lateral openings through which wires of the cable are accessible for circuit connection. This conduit is preferably stiff to be capable of maintaining its own shape, there being 20 desirably also a stiffening core within the cable.

I will explain my invention more fully by reference to the accompanying drawing showing the preferred embodiment thereof 25 and in which Fig. 1 is a front view of a timing switch equipped with the invention; Fig. 2 is a side view of the switch shown in Fig. 1 with the mounting therefor in section; Fig. 3 is a somewhat diagrammatic 30 view of the portion of the cable that is to surround the timer casing, before such portion is curled about the casing; Fig. 4 shows the metallic stiffening core and the contiguous portion of the flexible conductor united 35 therewith; Fig. 5 is a perspective view of the adjacent ends of the core and conductor of Fig. 4 in separated relation; Fig. 6 is a perspective view illustrating the structure as it appears in Fig. 1 with the timing 40 switch casing and the support for such casing removed; and Fig. 7 is a sectional view on line 7—7 of Fig. 6.

Like parts are indicated by similar characters of reference throughout the different 45 figures.

The timing switch illustrated is provided with any suitable support 1 in which an engine driven shaft 2 is mounted to turn. This engine driven shaft is suitably connected with a traveling contact 3 which may 50 be in the form of a roller suitably connected with one terminal of a source of current that is to be successively included in circuit with the contacts of spark plugs in the cylinders of a multiple cylinder internal combustion engine. The shaft 2 terminates

within a timer casing 4 which is rotatable upon support 1 and houses the contact 3 suitably supported upon the contiguous end of shaft 2. This timing switch casing supports 60 a plurality of contacts 5 equal in number to the number of cylinders included in the engine equipped with the switch, in this instance four. The casing 4 is formed with the usual cavity that receives a similarly shaped portion formed in a retaining spring 8, all as is understood by those skilled in the art. The casing is turned by a timing lever 9 that is 65 in the form of a rod having an end which passes through an ear 10 formed upon the casing. The conductors 11, each individual to and connected with a contact 5, are assembled into a cable and pass through a conduit 12 which partially surrounds the 70 timing casing, the conductors 11 terminating in or being connected with metallic terminals 13, each conductor having such a terminal individual thereto. These terminals 80 are clamped between the nuts 14 of binding posts that are respectively individual to the contacts 5.

All of the conductors 11, except one, preferably are entirely formed of tinsel wire so 85 as to be quite flexible. The conductor 11 which is not entirely formed of tinsel includes a stiff section 15 which is preferably a brass rod in the nature of a core that will retain the shape imparted to it and the similar shape of the cable portion of which it 90 forms a part. The stiff conductor section 15 desirably has one end formed into a half sleeve 16 as indicated in Fig. 5. The complementary tinsel portion of the corresponding conductor 11 is received in this half 95 sleeve and is soldered, whereby the section 15 becomes an electrical continuation of one of the conductors 11. The conduit portion 12 is long enough to provide the part of the cable which surrounds the casing with a stem 100 17 which extends a sufficient distance away from the casing to permit of the attachment thereto of the flexible tube 18.

The conduit section 12 extends for a short distance within the tubing 18, a sleeve 19 105 of rubber completing the joint between the two conduit sections and tending to prevent their separation. The stiffening core 15 is desirably almost co-extensive with the conduit section 12, extending considerably into 110 the bore of the sleeve 19, whereby the cable portion 17 is also made stiff. By this con-

struction that portion of the cable which is assembled with the timer casing is made rigid with respect thereto, while the continuing part of the cable that is within the 5 tubing 18 is sufficiently flexible readily to permit of the spark advancing and receding adjustments of the timer casing.

In assembling the conductors within the conduit section 12, the three completely flexible wires 11 are first placed within the bore of the conduit section 12, whereafter the rigid section 15 of the remaining conductor 11 is easily forced into position. The stiff section of the cable may be brought to suitable 10 shape apart from the timer casing, the shape of this part of the cable being maintained by the stiffening core 15 whether the cable is assembled with the timer switch casing or not.

While I have herein shown and particularly described the preferred embodiment of my invention I do not wish to be limited to the precise details of construction shown as changes may readily be made without departing from the spirit of my invention, but 20 having thus described my invention I claim as new and desire to secure by Letters Patent the following:—

A cable provided with an enclosing conduit having a portion formed with lateral 30 openings distributed along the same through which wires of the cable are accessible for circuit connection, said cable also having a stiffening core in its conduit.

In witness whereof, I hereunto subscribe 35 my name this 29th day of November A. D., 1921.

CHARLES L. LILLEBERG.
